Be it known that I, JAMES D. FRARY, of Bridgeport, in the county of Fairfield and State of Connecticut, have invented a new Design for Pocket-Knife Handles; and I do hereby declare the following, when taken in connection with the accompanying drawing, to be a full, clear, and exact description of the same, and which said drawing constitutes part of this specification, and represents a design for the side.

This invention relates to a design for the handle of pocket-knives, and particularly to that class which are made from cast metal; and it consists in the ornamentation of the

On the side, as seen in the figure, there is a raised figure representing a sailor in a standing position. Below the figure is a scroll, on which is the name "Ralph."
